(57) **CLAIM**

We claim the ornamental design for a spinning top, as shown and described.

DESCRIPTION

FIG. 1 is a perspective view of the spinning top showing our new design.

FIG. 2 is a side view of the spinning top shown in FIG. 1. A view of the other side of the spinning top is the same as FIG. 2.

FIG. 3 is a top view of the spinning top shown in FIGS. 1-2; and,

FIG. 4 is a bottom view of the spinning top shown in FIGS. 1-3.

The broken shading lines shown in the drawing(s) represent the three-dimensional contour of the design, and are not intended to indicate surface decoration.
